UNITED STATES PATENT OFFICE.

FRED A. PUTNAM, OF MELROSE, MASSACHUSETTS.

METHOD OF MAKING GOLD OR OTHER METAL LEAF IMPRESSIONS.

1,243,553.

Specification of Letters Patent.

Patented Oct. 16, 1917.

Application filed June 1, 1917. Serial No. 172,228.

To all whom it may concern:

Be it known that I, FRED A. PUTNAM, a citizen of the United States, residing at Melrose, county of Middlesex, State of Massachusetts, have invented an Improvement in Methods of Making Gold or other Metal Leaf Impressions, of which the following description, in connection with the accompanying drawing, is a specification, 10 like characters on the drawing representing like parts.

This invention relates to a process or method of applying gold leaf to leather, cloth, paper or other similar material thereby to make an impression thereon, and the object of the invention is to provide a novel process by which a sharp, clear-cut and burnished impression can be quickly made without any loss of material.

20 One method which is now commonly used in making gold leaf or other metal leaf impressions on material consists in first applying a coating of sizing to the material, then laying the gold leaf or other metal leaf over the sized portion of the material and subsequently applying a heated die to the metal leaf thereby causing the portion thereof with which the die contacts to adhere to the material and make the metal leaf impression thereon.

In order to finish the impression made by this method it is necessary to brush off from the material all of the metal leaf except that with which the die had contact, and this operation entails more or less loss which is a considerable factor where the metal leaf used is gold leaf. Furthermore, it sometimes happens that the metal leaf will stick to the sized material at other places than 40 that at which the die member acts on the metal leaf, and as a result, the impression is given a somewhat smeared appearance.

In order to avoid the sizing of the material before applying the metal leaf thereto, 45 it has been proposed to affix the metal leaf to a thin paper backing and to provide a coating of sizing either on the exposed face of the metal leaf or between the metal leaf and the backing so that when the heated die is 50 pressed against the backing the metal leaf will be separated from the backing at the points where the die contacts therewith, and such separated portions of the metal leaf will be caused to adhere to the material.

55 One of the advantages of this method of procedure is that there is no waste of the

metal leaf because when the impression is made only that portion of the metal leaf corresponding to the impression will be separated from the backing, the rest of the 60 metal leaf still being retained on the backing.

In order to cause the metal leaf to adhere firmly to the material it is necessary to subject the die to considerable pressure and 65 where the die acts on the gold leaf through the paper backing, the pressure of the paper against the gold leaf has a tendency to reproduce on the gold leaf a representation of the surface of the paper, thus detracting 70 from the desired brilliancy or luster of the printed impression.

My present invention provides a novel method of making a gold leaf impression which does not involve the step of first sizing 75 the material and by which a brilliant lustrous impression can be made.

In accordance with my invention, I first apply the gold leaf or other metal leaf to the material on which the impression 80 is to be made and then I heat the die with which the impression is to be made and apply a coating of sizing thereto and then bring the sized heated die against the gold leaf with sufficient pressure to make 85 the desired impression. Then I remove the die and apply another coating of sizing thereto and then bring the sized die a second time against the gold leaf or other metal leaf. I will preferably use metal leaf which 90 is secured to a paper backing, and when this is the case, the sizing on the die will during the first impression penetrate the paper and also the metal leaf sufficiently to cause the portions of the metal leaf which are subjected to the pressure of the die to separate 95 from the paper backing and to adhere firmly to the material. After the first impression the paper backing is removed and the sized die is then brought directly against the 100 metal leaf which has been transferred to the material, and this second impression gives a smooth surface to the impression and removes therefrom any traces of the impression that might be made by the paper. 105 A bright burnished impression is thus produced without the loss of any metal leaf and which has a clear-cut outline.

In order to give an understanding of the invention I have illustrated in the drawings 110 more or less diagrammatically one manner of practising the same which will now be de-

scribed, after which the novel features will be pointed out in the appended claims.

Figure 1 shows in perspective view some of the implements by which my improved process may be carried out;

Figs. 2, 3, 4 and 5 illustrate different steps in the process;

Fig. 6 is a perspective view of the gold or metal leaf.

13 The material on which the impression is to be made is shown at 1 and this may be leather, cloth, paper or any other similar material. The gold leaf or other metal leaf is indicated at 2 and I have shown it as applied to and supported by a backing 3 of porous material, such, for instance, as thin porous paper. The metal leaf and paper are shown as in the form of a strip which is rolled up into the roll 4. 5 indicates a platen or work-support on which the material 1 is supported while the impression is being made, and 6 is a die member having type characters 7 thereon. The die member is preferably heated by some suitable means as usual when making metal leaf impressions.

In carrying out my method the material is first placed on the platen or work-support 5 and the metal leaf strip is then placed on said material with the metal leaf in contact therewith. No sizing is applied to the material so that the portion of the material against which the metal leaf rests is in its natural condition. A coating of sizing is then applied to the face of the die 6 and the sized die is then pressed firmly against the backing 3 and during this operation the sizing on the face of the die will penetrate the backing 3 and also the metal leaf 2 sufficiently to cause the portions of the metal leaf which are subjected to the pressure of the die to separate from the backing 3 and to adhere to the material 1. The die 6 is then separated from the material and the strip of metal leaf is removed after which another coating of sizing is applied to the die and the sized die is brought directly against the metal leaf impression which has been formed on the material. In making the first impression the pressure of the die against the backing will tend to cause it to reproduce on the metal leaf a representation of the surface of the backing. When the sized die makes its second impression it acts directly on the metal leaf and operates to iron or smooth the surface of the latter, thus producing a bright, burnished impression and eliminating any traces which the paper backing may have left on the metal leaf. A clear-cut highly-burnished impression is thus produced without the loss of any metal leaf and without the necessity of using any more sizing than is necessary to cause the metal leaf to adhere to the material.

65 The operations of manipulating the

metal leaf so as to bring it into and out of operative position and of sizing the die at proper times may be accomplished by various means without departing from the invention. The devices herein shown are somewhat similar to those illustrated in my co-pending application Ser. No. 57,360, filed October 22, 1915. The strip of gold leaf and its backing are carried in a swinging carrier 8 and as the strip is used it is unwound from the roll 4 and wound onto a roll 9. The sizing of the die is accomplished by means of a sizing roll 10 which is sustained in a swinging frame or carrier 11. In carrying out my improved process the swinging carriers may be sustained on a suitable machine similar to that illustrated in my above-mentioned co-pending application and which causes them to have the cycle of operations indicated in Figs. 1 to 5 inclusive.

Fig. 1 shows the parts in position to receive the material. After the material is in position on the platen or work-support 5, then the swinging carriers 8 and 11 move forwardly carrying the gold leaf strip between the raised die 6 and the work and in front of the latter and bringing the sizing roll 10 into contact with the face of the die 6, as shown in Fig. 2. This results in applying a coating of sizing to the heated die 6. The carriers then swing backwardly and the carrier 8 is brought to rest with the metal leaf strip directly over the material 1 and beneath the die 6, as shown in Fig. 3. The heated die 6 then descends to make the first impression, during which the metal leaf which constitutes the impression is separated from the backing and caused to adhere to the material. The die 6 is then raised and the carriers 8 and 11 swing forwardly again into the position shown in Fig. 4, thus applying a second coating of sizing to the die. The carriers then swing backwardly into the position shown in Fig. 5, and during this backward movement the carrier 8 moves sufficiently to carry the metal leaf out of the path of movement of the die. The die then descends and is brought into direct contact with the metal leaf which has been separated from the backing and caused to adhere to the material by the former movement of the die. This second operation gives the impression the highly desirable burnished appearance. It will be understood, of course, that the practice of my improved method is not limited to the use of any particular devices or apparatus, and that the implements illustrated in the drawings have been shown merely for the purpose of giving a better understanding of the invention.

I have shown at 12 a rotary plate with which the sizing roll 10 is brought into contact at each backward movement thereof.

and by which the requisite sizing is supplied to said roll.

I claim:

1. The method of making a metal leaf impression on material which consists in applying metal leaf directly to unsized material, applying a coating of sizing to a heated die member, pressing the sized die member against the metal leaf thereby to cause 5 the portion of the latter which is subjected to the pressure of the die member to adhere to the material, withdrawing said die member, applying a second coating of sizing thereto, and then again pressing the sized 10 die member against the metal leaf impression made by the first operation of said die member.

2. The method of making a metal leaf impression on material which consists in providing a strip of metal leaf secured to a 20 backing of porous paper, placing said strip on the unsized surface of the material with the metal leaf resting against the face of the material, applying a coating of sizing to 25 a heated die member, pressing said sized die member against the paper backing whereby the sizing will penetrate the backing and metal leaf and causing the portion of the

metal leaf against which the die member acts to adhere to the unsized material, with- 30 drawing the die member and the strip, and then pressing said die member directly against the metal leaf impression formed by the first operation of said die member.

3. The method of making a metal leaf im- 35 pression on material which consists in providing a strip of metal leaf secured to a backing of porous paper, placing said strip on the unsized surface of the material with the metal leaf resting against the face of 40 the material, applying a coating of sizing to a heated die member, pressing said sized die member against the paper backing where- 45 by the sizing will penetrate the backing and metal leaf and causing the portion of the 50 metal leaf against which the die member acts to adhere to the unsized material, with- drawing the die member and the strip, ap- 55 plying a coating of sizing to said die mem- ber and then pressing the sized die member directly against the metal leaf impression on the material thereby to burnish it.

In testimony whereof, I have signed my name to this specification.

FRED A. PUTNAM.
